COATED NONFERROUS METAL AND METHOD AND MATERIAL FOR MAKING THE SAME

Robert R. Tanner, Highland Park, and Herman J. Lodeesen, Detroit, Mich., assignors to Metal Finishing Research Corporation, Detroit, Mich., a corporation of Michigan

No Drawing. Application July 14, 1932,
Serial No. 622,454

16 Claims. (Cl. 148—6)

This application relates to the coating of non-ferrous metals, particularly lead, tin, cadmium and alloys thereof, with substantially integral coatings of salts of the metal formed in situ on the surface thereof and adapted to form paint-holding coats.

More particularly the application relates to coated lead, tin, cadmium or their alloys having coatings formed by the action of a solution of an organic acid with a suitable accelerator or accelerators.

In a co-pending application of applicant, Robert R. Tanner, there is disclosed and claimed a method of coating iron, zinc, or their alloys, with an organic acid, an accelerator being employed preferably, although not necessarily, with certain of the acids. The organic acids found suitable for this purpose comprise the dicarboxylic and hydroxy-dicarboxylic acids of the aliphatic series and carboxylic, phenolic-carboxylic and sulphonic acids of the aromatic series, the useful carboxylic acids of the aromatic series being chiefly the mono-carboxylic acids. None of these acids alone has been found to produce a paint-holding coat on a panel of lead, or of tin. Applicants have discovered, however, that these metals and their alloys can be coated by acids of the above list when properly accelerated. Applicants have further discovered that cadmium can be coated by the same acids.

The most important of the acids within the list above indicated are oxalic, malonic, succinic, glutaric, adipic, malic, tartaric, benzoic, salicylic, gallic, tannic, benzene-sulphonic and similar sulphonic acids. The accelerators suitable or necessary for producing the desired coats may be divided into two classes, first, those comprising soluble compounds containing a metal and, second, those comprising oxidizing agents.

Of the first class, compounds containing copper are the most universally effective and easily obtained. In addition, antimony, silver, mercury, molybdenum and uranium and other metals below lead in the electro-motive series, with the exception of arsenic, bismuth and tungsten, act as accelerators for coating tin and lead. In addition to these, zinc, nickel, tin and lead all act as accelerators, in an oxalate bath, for example, for coating cadmium.

Amongst the oxidizing agents, the nitrates are

the most practical large class to be generally effective. In order to act as an accelerator, the oxidizing agent must be capable of oxidizing hydrogen as it is released by the action of the solution on the metal, and to do this, it must not exhaust its oxidizing power in oxidizing the acid. For example, potassium permanganate in an oxalic acid solution exhausts itself so rapidly in oxidizing the acid that it merely uses up the acid without accelerating the action of the solution. Other strong oxidizing agents act in the same way. Manganese dioxide is on the border line. It is reduced by oxalic acid, but it introduces manganese into the solution which generally helps some. The manganese introduced by potassium permanganate does not offset the detrimental effect of its action upon the acid.

Hydrogen peroxide is not reduced by oxalic acid rapidly below a temperature of 150° F. Above that temperature the beneficial effect is lost by the action of the oxidizing agent upon the oxalic acid.

The nitrates act as accelerators in the oxalic acid bath up to a temperature about 185° F., above which they oxidize the acid and lose their effectiveness.

To summarize, the test of the desirability of an oxidizing agent with a given solution is whether or not it exhausts itself and the acid, in oxidizing the acid or being reduced by the acid. This may be tested for carboxylic acids by introducing the oxidizing agent into a solution of the acid and observing whether or not CO₂ gas escapes. If it does, the oxidizing agent is exhausting itself and the acid. If this formation of CO₂ gas is rapid, the oxidizing agent is a detriment rather than a benefit. If no escape of CO₂ gas is observed, the oxidizing agent comes within the desirable class. If there is some slow formation of CO₂ gas, the agent may be helpful, but with the oxidizing agents on the border line, care must be taken to keep the solution below the temperature where the effectiveness of the oxidizing agent will be lost.

Another way of testing the action of the oxidizing agent upon the acid would be to test the acidity of the solution with a standard alkali before and after introducing the oxidizing agent.

While the principles stated above apply generally to tin, lead, cadmium and their alloys, there

are certain features in which the different metals respond differently to the treatment. Terne plate, which is iron coated with lead and tin, in general is coated at least as easily as either lead or tin alone by any given solution, and in some instances more readily than either of the metals alone. In general, the addition of an oxidizing agent, such as sodium nitrate, to a solution containing a compound of copper increases the acceleration and improves the coating over that formed by the solution with the copper alone. On terne plate, in particular, the coating formed by an oxalic acid solution is noticeably harder when a copper compound plus a nitrate is employed, than where a copper compound is employed alone. While this appears to be a general rule with the solutions of oxalic, malonic, glutaric, malic and salicylic acids, and is true of all the acids tested, when coating cadmium, there are some exceptions when coating tin, lead and terne plate.

For example, solutions of tannic or benzene-sulphonic acids produce better coatings on tin when accelerated by both a copper compound and an oxidizing agent than when accelerated by the copper compound alone, while these acids produce a better coating on lead and terne plate when accelerated by a copper compound alone than when accelerated by both a copper compound and an oxidizing agent. On the other hand, the use of both a copper compound and an oxidizing agent results in a better coating action of succinic, adipic, tartaric and benzoic acids upon lead or terne plate than the use of the copper compound alone, while with these same acids a better coating is produced on tin when a copper compound is used alone as an accelerator than when both the copper compound and an oxidizing agent are used. A solution of gallic acid, containing the copper accelerator alone, is superior in treating either tin or lead to the same solution with sodium nitrate added, but on terne plate not much difference was observed. It is difficult to coat lead with a solution of malic acid, and the addition of a copper compound and/or sodium nitrate, in proportions which render most of the other solutions readily operative, does not produce any satisfactory coat on lead. However, malic acid can be made to coat lead by employing a compound of mercury with sodium nitrate as accelerators. In this connection, it may be stated that mercury is deposited more readily and quickly than copper and, therefore, has a greater accelerating action where it is difficult to produce a coat without considerable acceleration. On the other hand, where the other accelerators are satisfactory, the use of mercury must be very carefully controlled in order to avoid excessive deposition and a smudgy coat.

For most commercial purposes, the most important acid of the series is oxalic acid, since that is as active as any in producing a coat and is the cheapest and most readily obtainable, and for most purposes requires less careful manipulation than the other acids.

There may be considerable variation in the concentration of the solutions but, in general, 15 grams of the acid per 100 cc. of water forms a satisfactory strength. A convenient way of adding a copper compound as an accelerator is to dissolve 5 grams copper sulphate in 100 cc. of water, and add sufficient of this solution to obtain the desired results. In general, 2 cc. of the copper sulphate solution added to 100 cc. of the acid solution is sufficient for the metallic accel-

erator. Ten grams sodium nitrate is, in general, sufficient to add to the 100 cc. acid solution as an oxidizing agent, but where the action is not readily obtainable, a greater amount may be added, for example, with a succinic acid solution, where the metal accelerator is omitted, it has been found desirable to add as much as 15 grams of sodium nitrate to the solution to obtain a satisfactory coating on tin. In general, the coating can be rendered harder by increasing the oxidizing agent. As previously noted, this does not work out satisfactorily where a metallic accelerator is used also, and where tin is being coated with succinic, adipic, tartaric, benzoic or gallic acid, or where lead is being coated with gallic, tannic or benzene-sulphonic acids.

In solutions such as indicated above, sodium nitrite is more effective than sodium nitrate in amounts under about 15 grams per 100 cc. of solution, but in larger amounts the nitrate is preferable.

The amount of metal compound desirable or permissible as an accelerator, varies widely with the surface being coated, the kind and strength of the acid used, the kind of metal accelerator used, and the kind and amount of oxidizing agent employed. In general, it may be stated that the accelerating metal is deposited as metal interspersed through the salt coating, and too great a proportion of the metal in the coating renders it smudgy. The amount of metal in the coating depends upon the relative speeds of deposition of the metal and formation of the salt coat. The deposition of the metal increases with increased acidity, while the formation of the salt coat is not correspondingly speeded up by increased acidity. For this reason, a greater amount of metal accelerator is permissible in a dilute acid solution than in a stronger acid solution. When the formation of the salt coat is speeded up, by use or increase of an oxidizing agent or otherwise, the amount of metal accelerator may be correspondingly increased without increasing the proportion of metal to salt in the coat.

Silver and mercury are deposited more rapidly than copper, under similar conditions and, therefore, silver or mercury should be used in less quantities than copper in an otherwise similar solution. Antimony, molybdenum and uranium may be used in larger quantities than can copper in a given solution.

It will be recognized that the above outlined principles may be followed to compound a wide variety of solutions by use of the various ingredients in different proportions. Oxalic acid is more active than many of the acids which it is possible to use, and is preferably employed in greater dilution. One formula which gives good results for commercial treatment of terne plate is 40 gals. of water, 5 lbs. of oxalic acid, 35 lbs. of sodium nitrate and $\frac{1}{2}$ oz. copper sulphate. It will be understood that this is given by way of example only.

In general, it is more difficult to coat tin and lead than it is to coat iron and zinc, as will be seen from comparing the disclosure in the co-pending application previously mentioned; but tannic acid and the accelerating compounds of mercury antimony, molybdenum and uranium are more effective in coating lead or tin than in coating iron or zinc.

The proportion of coatable metal, which is necessary in an alloy in order to make the alloy receive the coat properly, varies considerably with different combinations of metal. In general,

where two or more coatable metals are included in the alloy, the coating operation is fully as easy and satisfactory on the alloy as it would be upon the most easily coatable of the two metals. It is not always necessary to have as much as 50% of a coatable metal in the alloy in order to make the alloy receive a coating. This is particularly true with aluminum alloys, since an aluminum alloy containing much less than 50% of coatable metals may be readily coated by solutions, such as outlined above, although the pure aluminum is not coated by these solutions. Therefore in the appended claims, where metals and their alloys are claimed, it is to be understood that the term "alloys" is intended to cover any metal composition containing enough of the coatable metal to enable the alloy to receive the coating, even though there may be less than 50%.

What we claim is:—

- 20 1. An article having a surface of metal, of the class consisting of lead, tin, and cadmium and alloys thereof, coated with a coating the major portion of which is a salt formed in situ thereon, the base of the salt being of the metal that is coated and the acid radical being one of the group consisting of the dicarboxylic and hydroxy-dicarboxylic acids of the aliphatic series and the carboxylic, phenolic carboxylic, and sulphonic acids of the aromatic series.
- 25 2. An article in accordance with claim 1, and in which the coating contains, interspersed through the salt coating, particles of a metal of the group comprising copper, silver, mercury, antimony, molybdenum, and uranium.
- 30 3. An article in accordance with claim 1, and having the metal surface of cadmium and the coating containing a metal of the group consisting of zinc, nickel, tin, lead, antimony, molybdenum, uranium, copper, silver and mercury.
- 35 4. The method of coating a surface of a metal, of the group consisting of lead, tin, cadmium and their alloys, which consists in treating said surface with a solution containing, as its chief coating chemical, an acid, of the group consisting of the dicarboxylic and hydroxy-dicarboxylic acids of the aliphatic series and the carboxylic, phenolic-carboxylic and sulphonic acids of the aromatic series, and an accelerating agent of the group consisting of soluble compounds of metals of the group consisting of copper, silver, mercury, molybdenum, antimony, and uranium and soluble oxidizing agents which are not reduced by the acid in the solution, regulating the amount of any accelerated soluble compound of metal in the solution, inversely as to the free acidity of the solution and directly as to the rate of formation of a salt coating by the solution, so as to expedite the formation on the metal to be coated of a difficultly soluble salt of the metal being coated and the acid being employed, without depositing more
